UNITED STATES PATENT OFFICE.

CHARLES J. HENSCHEL, OF BLOOMFIELD, AND CHARLES MESSICK, OF HACKENSACK,
NEW JERSEY, ASSIGNEES TO SAID HENSCHEL.

GEOMETRICALLY-PROGRESSIVE CONTROL SYSTEM.

1,139,972.

Specification of Letters Patent.

Patented May 18, 1915.

Application filed March 24, 1914. Serial No. 826,862.

To all whom it may concern:

Be it known that we, CHARLES J. HENSCHEL, a citizen of the United States, residing at Bloomfield, in the county of Essex and State of New Jersey, and CHARLES MESSICK, a citizen of the United States, residing at Hackensack, in the county of Bergen and State of New Jersey, have invented certain new and useful Improvements in Geometrically-Progressive Control Systems, of which the following is a specification.

Our invention relates to control systems of the type sometimes designated as remote control systems, and used for various purposes, such as signaling, or broadly speaking, for causing a movable member of any kind to execute a movement analogous to a corresponding movement made by some other movable member at a point located remote therefrom. In such systems there is usually a driving member, located at a point which may be designated as a transmitting station, and a driven member located at another point remote from the transmitting station, and which may be considered as a receiving station. The driven member, located at the receiving station, executes a movement simulating, or at least in some manner representing, a more or less analogous movement made by the driving member at the transmitting station—the movements of this driving member being oftentimes, though not necessarily, made by hand, or at least controllable at the will of an operator located at the transmitting station.

By our invention, we employ a system of the type above mentioned, and provide in such system a number of individual controlling members, associated with different paths of communication each extending from the transmitting station to the receiving station, and under control of the driving member at the transmitting station for the purpose of actuating the driven member at the receiving station. The several controlling members are arranged to actuate quantitatively the driven member at the receiving station, the degree of actuation of said driven member, however, being different for each of said controlling members. By this means, we so maintain the driven member at the receiving station under control of any or all of the individual control-

ling members that the driven member may execute movements totalizing the aggregate work of all of the controlling members which, at any particular moment, are selectively thrown into action.

By arranging our system as just stated, a large number of separate and distinguishable movements may be executed by the driven member at the receiving station, for a given number of individual controlling members and separate paths of communication. For instance, with each additional controlling member used in the relation stated the aggregate number of separate movements, capable of execution by the driven member at the receiving station, may be doubled. Therefore the number of separate indications possible of execution at the receiving station may thus be in geometrical ratio to the number of separate controlling members and paths of communication employed.

While our system admits of a great variety of uses, and may be employed in many distinct relations, we will for the sake of conciseness show it as embodied in a single representative mechanism, namely, a signaling system adapted for use, for instance, as a ship's telegraph. In this particular form of our device the driven member at the receiving station is an indicator capable of measuring quantitatively; the driving member, located at the transmitting station, is a hand operated electric switch; the individual controlling devices for affecting the indicator are a number of solenoids each provided with a movable core, the stroke of each core being different, in geometrical ratio, from that of other cores; and the several paths of communication being the same number of electric circuits, selectively under control of the switch at the transmitting station, and connected respectively with said solenoids; these solenoids being operatively connected with the indicator in such manner that the indicator may register an indication representing the aggregate length of stroke of any or all of the solenoid cores.

Reference is made to the accompanying drawings forming a part of this specification, and in which like letters indicate like parts, the figure representing the ship's telegraph complete.

A switch board 8, located at the trans-

mitting station, is provided with a number of display marks 0, 1, 2, 3, 4, 5, 6, 7, such display marks in this instance being eight in number.

5 A contact ring 9 is mounted upon the switch board 8, and adjacent this ring is a revoluble switch arm 10, held in position by a pivot pin 11, and provided with a handle 12 whereby it may be turned or swung 10 to different angles. The switch arm 10 carries a contact bar 13 and strip 14 of insulating material, whereby the arm is insulated. The switch board 8 is provided with a number of stationary contact members 15, 16, 17, each of which is connected with a wire 18 extending to the receiving station shown in the upper portion of the figure. Another stationary contact member 19 is connected with this wire by a short 20 wire 20. A number of other stationary contact members 21, 22, 23 are connected with a wire 24. A stationary contact member 25 is connected with this wire 24 by a wire 26. Other stationary contact members 27, 28, 25 29, 30 are connected with a wire 31, leading also to the receiving station.

30 A wire 32 is connected with the ring 9, and with a source of electricity 33, which in this instance is a dynamo. A wire 34 leads from this dynamo to the receiving station.

35 A board 35, located at the receiving station, supports the various parts employed at said station. Mounted upon this board are a number of solenoids 36, 37, 38 provided with movable cores 39, 40, 41. The solenoids in question are connected with the wires 18, 24, 31. They are also connected, by wires 42, 43 and 44, with the wire 34, which thus acts as a return wire for all of 40 the solenoids.

45 Secured to a fixed pin 46, carried by the board 35, is a flexible connection 47, preferably a chain. This flexible connection also engages a pulley 48 for the purpose of actuating the latter positively. A dial 49, carried by the board 35, is provided with display legends, in this instance eight in number, namely, 0, 1, 2, 3, 4, 5, 6, 7, corresponding to the display legends carried by the 50 board 8. A pointer 50 is mounted rigidly upon the pulley 48, and normally rests against a stop pin 51, and in such position as to designate the legend 0. The pulley 48 is mounted to turn upon a pin 52.

55 Associated with the solenoids 36, 37, 38, are sheave wheels 53, 54, 55, which are respectively engaged by the flexible connection 47. Each sheave wheel is journaled in a bearing 56 provided with a cross bar 60 57, each core 39, 40, 41, carrying one such bearing, sheave wheel and cross bar. Adjacent each cross bar 57 is a stop pin 58, for limiting travel of the adjacent core in one direction. The travel of each core in the 65 opposite direction is limited by the top por-

tion of the solenoid against which the cross bar lodges as the core is drawn downwardly to the limit of its stroke.

Two other pulleys 59, located over the solenoids, are engaged by the flexible connection 47. This flexible connection, in engaging the various pulleys 48, 59, 53, 54, and 55, is wound sinuously back and forth. A weight 60, carried by the flexible connection 47, hangs below the pulley 48. This 75 weight maintains the flexible connection 47 taut at all times, and normally supports the various cores 39, 40, 41 in their respective uppermost positions. The relative degrees of play allowed the cores 39, 40, 41 respectively, is such that the core 40 is free to move twice as far as the core 39, and the core 41 is adapted to travel double the distance the core 40 is capable of traveling. 80

While in this instance we show only three 85 solenoids, any larger number may be employed. Each successive solenoid added should have its core so arranged as to travel double the maximum distance traveled by any preceding core. For instance, if the 90 core 39 has a travel of one inch, the core 40 should travel two inches, the core 41 should travel four inches, and any successive cores added should travel eight inches, sixteen 95 inches, thirty-two inches, etc.—each successive core traveling double the distance of the one preceding it.

The parts are so proportioned and arranged that when the core 39 is drawn 100 downwardly by the solenoid 36, the pointer 50 travels a distance equal to the distance between any two successive legends on the dial 49. Each time the core 40 is drawn downwardly by the solenoid 37, the pointer 50 travels a distance representing two successive legends carried by the dial 49. A down-stroke of the core 41 causes the pointer 50 to move a distance represented by four successive legends carried by the dial in question. 11

The solenoids 36, 37, 38 may be energized either one at a time, or in groups of two or three at a time, and when energized in groups, their effect upon the flexible connection 47 and pulley 48 is cumulative, so that the pointer 50 registers an indication commensurate with the aggregate degree of travel of all of the cores affected at a particular moment. Therefore, by separately energizing each solenoid, and by energizing 12 differently-selected groups of the solenoids, the pointer 50 can be caused to register a large number of indications.

The precise number of indications which may be registered by a given number of solenoids increases in geometrical progression to the number of solenoids, as above explained. With a single solenoid, two indications can be made, one of these of course being the normal or so-called zero position. 13

With two solenoids, four indications can be made, including said zero position. With three solenoids, the number of indications increases to eight. With four solenoids, the number of indications possible would be sixteen—each successive solenoid added thus doubling the number of indications which could be made without it.

The sum of the respective distances traveled by the cores 39, 40, 41, or any of them, is equal to one half of the rotary travel of the pulley 48. This is because the leverage between the flexible connection 47 and the various pulleys is so apportioned that the rotary travel of the pulley 48 is twice the aggregate travel of any or all of the solenoid cores affected. The display legends carried by the dial 49 are therefore spaced apart accordingly. In other words, the indicating mechanism is properly calibrated so that its indications will be correct.

The operation of our device is as follows: The parts being assembled and arranged as shown and described, and the movable parts being in their respective normal positions, the switch arm 10 and the pointer 50, each occupy the so-called idle or zero position. Suppose, now, that the operator at the transmitting station wishes to signal the operator at the receiving station by causing the pointer 50 to move to the display legend 1. The transmitting operator grasps the handle 12 and turns the arm 10 into such position that the contact bar 13 engages the stationary contact member 15. This completes a circuit as follows: Source of electricity 33, wire 32, contact ring 9, contact bar 13, stationary contact member 15, wire 18, solenoid 36, wires 42 and 34, back to source of electricity 33. This circuit energizes the solenoid 36 and causes it to draw the core 39 downward to the limit of its travel. The pointer 50 is thus moved to the angular extent necessary to shift it to the display legend 1. Suppose, next, that the transmitting operator shifts the switch arm 10 to the display legend 2 carried by the board 8, so that the contact bar 13 engages the stationary contact member 21. The following circuit is thus completed: Source of electricity 33, wire 32, contact ring 9, contact member 13, stationary contact member 21, wire 24, solenoid 37, wires 43 and 34, back to source of electricity 33. This energizes the solenoid 37, and the pointer 50 moves around to the legend 2 on the dial 49. Assume, next, that the transmitting operator moves the switch arm 10 around to the legend 3 of the dial 8. The contact bar 13 now engages two stationary contact members 16 and 22. A circuit is thus completed as follows: source of electricity 33, wire 32, contact ring 9, contact bar 13, stationary contact member 16, wire 18, solenoid 36,

wires 42 and 34, back to source of electricity 33. This energizes the solenoid 36. Another circuit is completed as follows: source of electricity 33, wire 32, contact ring 9, contact bar 13, stationary contact member 22, wire 24, solenoid 37, wires 43 and 34, back to source of electricity 33. The circuit last traced energizes the solenoid 37. Both cores 39 and 40 are now drawn downwardly, the result being that the pointer 50 travels around to an extent commensurate with the aggregate influence of the two solenoids in question. The pointer 50, therefore, takes up such position as to designate the legend 3 upon the dial 49. If the operator at the transmitting station turns the switch arm 10 to the legend 4 at the bottom of the board 8, the contact bar 13 is brought into engagement with the stationary contact member 27. The following circuit is thus completed: source of electricity 33, wire 32, contact ring 9, contact bar 13, stationary contact member 27, wire 31, solenoid 38, and wires 44 and 34, back to source of electricity 33. The solenoid 38, being thus energized, draws the core 41 downwardly to the lower limit of its travel, so that the pointer 50 now moves twice as far as the core 40 could move it, or four times as far as it could be moved by the core 39. The pointer 50, therefore, designates the legend 4, at the bottom of the dial 49. Suppose, next, that the switch arm 10 be moved to the legend 5 of the board 8, so that the contact bar 13 now engages the stationary contact members 17 and 28. A circuit is thus completed as follows: source of electricity 33, wire 32, contact ring 9, contact bar 13, stationary contact member 17, wire 18, solenoid 36, and wires 42 and 34, back to source of electricity 33. Another circuit is also completed as follows: source of electricity 33, wire 32, contact ring 9, contact bar 13, stationary contact member 28, wire 31, solenoid 38, and wires 44 and 34, back to source of electricity 33. The two circuits just traced energize the solenoids 36 and 38, so that the cores 39, 41 are drawn downwardly, and the pointer 50 is moved to an extent representing the aggregate travel of the two cores. The pointer therefore moves to the legend 5 of the dial 49. The switch arm 10 may next be moved, say, to the legend 6 carried by the board 8. This brings the contact bar 13 into engagement with the two contact members 23 and 29. A circuit thus completed may be traced as follows: source of electricity 33, wire 32, contact ring 9, contact bar 13, contact member 23, wire 24, solenoid 37, and wires 43 and 34 back to source of electricity 33. Another circuit may also be traced as follows: source of electricity 33, wire 32, contact ring 9, contact bar 13, stationary contact member 29, wire 31, solenoid 38, and

wires 44 and 34, back to source of electricity 33. As the two circuits just traced include respectively the solenoids 37 and 38, these solenoids are energized, the cores 40 and 41 are drawn downwardly, and the pointer 50 moves to an extent representing the aggregate travel of these two cores. The pointer 50, therefore, moves to the legend 6, upon the dial 49. Lastly, suppose that the switch arm 10 is moved around to the legend 7 carried by the board 8. The contact bar 13 now rests upon three contact members 19, 25 and 30. A circuit thus completed is as follows: source of electricity 33, wire 32, contact ring 9, contact bar 13, stationary contact member 19, wire 20, wire 18, solenoid 36, wires 42 and 34, back to source of electricity 33. Another circuit completed may thus be traced as follows: source of electricity 33, wire 32, contact ring 9, contact bar 13, stationary contact member 25, wires 26, 24, solenoid 37, wires 43 and 34, back to source of electricity 33. A third circuit, also now completed, may be traced as follows: source of electricity 33, wire 32, contact ring 9, contact bar 13, stationary contact member 30, wire 31, solenoid 38, and wires 44 and 34, back to source of electricity 33.

30 As the three circuits just traced include the three solenoids 36, 37, 38, these solenoids are energized, the cores 39, 40 and 41 are drawn downwardly, and the pointer 50 moves to an extent commensurate with the aggregate travel of all three of the cores, and stops at the legend 7.

Whenever, after making any indication above described, the switch arm 10 is restored to its normal position, or even moved 40 sufficiently in either direction to disconnect the contact bar 13 from the stationary contact member or members engaged by said contact bar, the weight 60, by turning the pulley 48, causes the pointer 50 to move into 45 its normal position, and to indicate the legend 0. In doing this the weight 60 also restores all the movable parts at the receiving station to their respective normal positions indicated in the drawing.

50 As elsewhere indicated, we do not limit ourselves to the precise mechanism here shown and described, the scope of our invention being commensurate with our claims.

Having thus described our invention, what 55 we claim as new and desire to secure by Letters Patent is as follows:

1. The combination of a sending indicator provided with and capable of indicating several characters at a sending station, and 60 other indicator provided with and capable of indicating several corresponding characters at a receiving station, and a geometrically progressive series of means whereby the receiving indicator may be operated at 65 the sending indicator to indicate a character

similar to the character indicated by the sending indicator.

2. The combination of a sending indicator provided with and capable of indicating several characters at a sending station, another indicator provided with and capable of indicating several corresponding characters at a receiving station, and a geometrically progressive series of electromagnetic means whereby the receiving indicator may 75 be operated at the sending indicator to indicate a character similar to the character indicated by the sending indicator.

3. In a geometrically progressive signaling system the combination of an indicator 80 located at a sending station and provided with a plurality of legends and with means for indicating said legends individually, an indicator located at a receiving station and likewise provided with a plurality of legends 85 and with means for indicating the same individually, and a plurality of electrically operated controlling members each under control of said indicator at said sending station and electrically connected with said indicator at 90 said receiving station, each of said controlling members being provided with means for actuating said last mentioned indicator quantitatively to a predetermined extent independently of the others. 95

4. In a geometrically progressive signaling system, a sending station provided with a plurality of legends and with means for indicating said legends individually, an indicator located at a receiving station and likewise provided with a plurality of legends and with means for indicating the same individually, a plurality of electrically operated magnetic members severally connected to said second mentioned indicator for actuating the same quantitatively either singly or in groups, and electrical connections from said first mentioned indicator to said controlling members, for energizing the latter. 100

5. The combination of a receiving indicator provided with a number of legends and with means including a driven member for indicating said legends individually, a plurality of solenoids, a movable core for each solenoid, each of said cores having a 11 limit of travel varying in geometrical ratio from the limit of travel of others of said cores, means for enabling movements of said cores to actuate said driven member so as to cause said driven member to make a 12 quantitative movement commensurate with the aggregate travel of all of said cores which may be actuated at a particular movement, circuits connected with said solenoids and extending to a distance from said 12 indicator for energizing said solenoids, and a sending indicator connected with all of said circuits for selectively energizing predetermined groups of said circuits, said sending indicator being provided with 13

legends and with means for indicating said legends in the same order of succession as the legends indicated at the receiving station.

- 5 6. A signaling system comprising an indicator located at a receiving station and provided with legends and with means for indicating the same individually, mechanism including a plurality of solenoids and
 10 movable cores for actuating said indicator, one of said cores having greater travel than another so that the indication registered by said indicator is greater for one solenoid than for another, a plurality of circuits each connected with one of said solenoids and extending to a distance therefrom, and indicating mechanism located at a distance from said first mentioned indicator and connected with said circuits in order to energize the same, said indicating mechanism being provided with legends corresponding to said first mentioned legends and further provided with means for indicating them individually.
- 15 7. A signaling system comprising a receiving indicator provided with a plurality of legends, a revolute member for actuating said indicator so as to indicate any one of said legends, a flexible cord connected with said revolute member in order to turn the same, a plurality of magnetic cores connected to said cord and arranged to actuate said cord to different extents varying in geometrical ratio, solenoids for actuating said cores, a plurality of electric circuits each connected with a particular solenoid for energizing the same, and selective switch mechanism located at a distance from said

driven member and connected with said circuits for energizing the latter, said selective switch mechanism being provided with legends corresponding to said first

15 mentioned legends, for the purpose of indicating a legend corresponding to the one indicated at the receiving station.

8. In a signaling system the combination of an indicator located at a receiving station and provided with legends and with means for indicating said legends, mechanism including a plurality of solenoids with
 20 movable cores for actuating said indicator quantitatively, the respective limits of travel of the several solenoids varying in geometrical ratio in order to differentiate said legends as indicated, electric circuits connected with said solenoids for energizing the same, selective switch mechanism located at a sending station and connected with said circuits in order to energize the same individually or in predetermined groups accord-
 25 ing to the legend to be indicated at the receiving station, and indicating mechanism located at the sending station and coacting with said selective switch mechanism, for making indications corresponding to the legends indicated at the receiving station.

In testimony whereof we have signed our names to this specification each in the presence of two subscribing witnesses.
